CLAIM

The ornamental design for a display screen with animated graphical user interface, as shown and described.

DESCRIPTION

FIG. 1 is a front view of a display screen with animated graphical user interface showing a first image in a sequence of my new design;

FIG. 2 is a second image thereof;

FIG. 3 is a top plan view of an exemplary portable device for the display screen shown in FIGS. 1 and 2;

FIG. 4 is a right side elevation view of the exemplary portable device in FIG. 3;

FIG. 5 is a left side elevation view of the exemplary portable device in FIGS. 3-4;

FIG. 6 is a rear elevation view of the exemplary portable device in FIGS. 3-5; and,

FIG. 7 is a bottom plan view of the exemplary portable device in FIGS. 3-6.

The broken lines showing the portable device illustrates environmental subject matter, whereas the broken lines showing a display screen and elements of the graphical user interface illustrate portions of the article. No subject matter depicted in broken lines form part of the claimed design. The appearance of the animated design sequentially transitions between the images shown in FIGS. 1-2, respectively. The process or period in which one image transitions to another forms no part of the claimed design.
